(57) **CLAIM**

We claim the ornamental design for a camera enclosure, as shown and described.

DESCRIPTION

FIG. 1 is a front perspective view of a camera enclosure showing our new design.

FIG. 2 is a back perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof; and,

FIG. 8 is a bottom view thereof.

The broken lines represent portions of the camera enclosure that form no part of the claimed design.
